(57) **CLAIM**

The ornamental design for a sandal, as shown and described.

DESCRIPTION

FIG. 1 is a top perspective view of a sandal showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top plan view of the sandal in another configuration of use.

The short broken lines shown on the claimed portions depict stitching, which forms no part of the claimed design. The dash-dash broken lines in the drawings depict portions of the sandal that form no part of the claimed design.

1 Claim, 8 Drawing Sheets
